UNITED STATES PATENT OFFICE

EDWARD F. SCHULTZ, OF CHICAGO, ILLINOIS

DESIGN FOR A CANOPY FOR FUNERALS

Application filed December 15, 1930. Serial No. 38,003. Term of patent 14 years.

To all whom it may concern:

Be it known that I, EDWARD F. SCHULTZ, a citizen of the United States, residing at Chicago, in the county of Cook and State of Illinois, have invented a new, original, and ornamental Design for a Canopy for Funerals, of which the following is a specification, reference being had to the accompanying drawings, forming part thereof.

I claim:

The ornamental design for a canopy for funerals as shown.

EDWARD F. SCHULTZ.
